UNITED STATES PATENT OFFICE.

GEORGE O. SANBORN, OF PETALUMA, CALIFORNIA.

DESIGN FOR A BOTTLE.

SPECIFICATION forming part of Design No. 21,524, dated May 10, 1892.

Application filed March 7, 1892. Serial No. 424,088. Term of patent 14 years.

To all whom it may concern:

Be it known that I, GEORGE O. SANBORN, a citizen of the United States, residing at Petaluma, in the county of Sonoma and State of California, have invented and produced a new and original Design for a Bottle, of which the following is a specification, reference being had to the accompanying drawing, forming a part thereof.

10 The drawing represents a perspective view of the design, the said representation being all that is deemed necessary to fully illustrate my invention.

15 The leading feature of my design consists in a bottle, the outside surface of which is corrugated, the corrugations running up and down from that portion near the center, where there is a round or oval smooth surface, with a continuation of a narrow smooth surface right

20 and left from the outside circumference of the

same around the bottle. The bottom part is slightly concave and smooth. Two parallel corrugations run round the central part of the bottle above the smooth surface and two just below the same, as the drawing shows. 25

A represents the bottle; b b b, the corrugations running up and down on the surface; c, c c, the smooth surface about the central part; e e, the parallel corrugations encircling the bottle above and below the smooth central 30 part.

What I claim, and desire to secure by Letters Patent of the United States, is—

The design for a bottle, as herein described and shown.

GEORGE O. SANBORN.
